PUSH ROD

Leonard J. Rosa, Detroit, Mich.

Application November 5, 1945, Serial No. 626,878

7 Claims. (CL. 123—90)

1

The invention relates to push rods of the type used in valve actuating mechanisms of internal combustion engines and to a method of making the same.

An important object of the invention is to provide a push rod that is strong and rugged in construction but exceedingly light in weight.

Another object of the invention is to provide a push rod that is simple in construction and inexpensive to manufacture.

Still another object of the invention is to provide an efficient method of making the push rod.

Yet another object of the invention is to provide a novel method of capping the ends of the push rod that effects a strong, rigid union between the caps and the terminal portions of the rod.

Other objects and advantages of the invention will be apparent during the course of the following description.

In the drawing, forming a part of this specification and wherein like numerals are employed to designate like parts throughout the same,

Figure 1 is a side elevation of a push rod embodying the invention, parts being broken away and shown in section for clearness of illustration.

Figure 2 is a side elevation of a tubular metal rod as it appears before the end caps are applied thereto.

Figure 3 is a fragmentary longitudinal sectional view through one of the end caps and a terminal portion of the tube showing the initial relationship of the parts during the capping operation.

Figure 4 is a view similar to Figure 3, but showing the end of the tube pressed into the cap.

Figure 5 is a view similar to Figure 4, but illustrating the relationship of the parts after the tube has been pushed farther into the cap.

Figure 6 is a view similar to Figure 5 but illustrating a subsequent step in the capping operation and showing the tube expanded radially into the circumferential enlargement provided in the side wall of the cap.

Figure 7 is a view similar to Figure 6 but illustrating the relationship of the parts during the final step of the capping operation and showing the tube folded or upset against the inner end of the cap.

Figure 8 is a longitudinal sectional view through a modified tube and cap showing the manner in which an oversize tube can be capped according to the present invention and illustrating the initial relationship of the parts during the capping operation.

Figure 9 is a view similar to Figure 8 but illustrating the relationship of the tube and cap after

2

the capping operation has been completed, and

Figure 10 is a longitudinal sectional view through a second modified tube and cap and showing the relationship of the parts after the final capping operation.

Considered in certain of its broader aspects, the invention comprises a push rod of the type shown in my copending application, Serial No. 548,267, which was filed August 5, 1944. However, the 10 push rod embodying the instant invention differs structurally from the push rod shown in the application and it is formed by an entirely different method.

According to the present invention, the terminal portions of a tubular metal rod are inserted 15 in preformed caps of relatively harder material and the parts subjected to an axially compressive force. The sockets of the caps are provided with spherically curved bottom portions and circumferential enlargements in at least a portion of their side walls so that application of force in the above manner first causes the ends of the tube to be pressed against the curved bottom portions of the caps. Since the caps are of relatively 20 harder material, this operation causes the ends of the rod to yield and follow the bottom surfaces of the sockets. When the resistance offered by the tube to further deformation becomes sufficiently great, its side wall expands radially into 25 the circumferential enlargements. Continued application of pressure then causes the portions of the tube extending from the caps to fold outwardly or upset against the inner ends of the caps. Preferably, the inner ends of the caps are 30 then compressed slightly to assure a snug, tight fit with the tube. The capping operation is completed and the caps are strongly and rigidly 35 united with the tube.

Obviously, there are a number of different ways 40 in which the tube and caps can be mechanically held or supported during the capping operation; however, this conveniently may be done by gripping the tube immediately behind the point at which the final upset occurs and then pressing 45 the caps toward each other whereby to subject the rod to an axially compressive force. The tube preferably is held mechanically by suitable gripping jaws and pressure is applied to the caps in any suitable manner such as by mechanically or hydraulically driven rams.

This method of forming the push rod permits 50 the finished product to be held to an accurate longitudinal dimension. If the jaws which grip the tube are accurately and uniformly spaced, 55 all the push rods will be brought to the same

longitudinal dimension since the final upset occurs in the portion of the tube extending between the end of the cap and the jaws. The method of forming the tube is such that it can be made automatically by mechanical means.

In practice, the caps are first formed, then hardened and preferably brought to an externally highly finished condition before they are applied to the tubes. Since the caps are small they can be economically manufactured and readily handled. The capping operation preferably is done cold so as not to affect the finish of the caps.

From the foregoing it will be apparent that the push rod embodying the instant invention comprises an elongated, relatively thin-walled metal tube which carries end caps of relatively hard metal and having circumferential enlargements in the side walls thereof.

The portions of the rod within the caps press against the ends of the latter, enter the circumferential enlargement in their side walls and have radial extrusions which bear against the inner ends thereof. The interlocking engagement thus provided by the deformed portions of the tube hold the caps solidly and permanently associated therewith.

For a more detailed description of the invention reference is had to the accompanying drawing wherein the numeral 20 designates a tubular metal rod and the numerals 22 and 24 designate caps on the ends of the rod. The rod 20 is formed from any suitable thin-walled tubing of sufficient strength to sustain the stresses to which it will be subjected in use, and the caps 22 and 24 are formed from a hardenable steel or other suitable metal which is relatively stronger than the rod. Each of the caps is preformed and has a spherically curved convex end portion 26 provided with an oil opening 28 and a cylindrical side wall 30 provided intermediate its ends with a circumferential enlargement 32.

If the rod 20 is of relatively small diameter, the composite push rod is preferably formed in the manner illustrated in Figures 3-7. A suitable tubular rod 20 somewhat shorter than the finished product is selected and placed between suitable gripping jaws (now shown) which engage it at accurately spaced, predetermined points. The caps 22 and 24 are then applied to the projecting portions of the rod, as shown in Figure 3. These caps may be applied either singularly or simultaneously; however, in the interest of brevity and clarity, the description will be limited to the manner in which cap 22 only is applied. It will be understood that, in practice, it is contemplated that both of the caps may be applied in the same manner and at the same time.

The cap 22 can easily be pushed onto the tube 20 to the position shown in Figure 3. The tube fits snugly in the mouth portion 34 and passes readily through the circumferentially enlarged portion 35. However, the portion 38 of the side wall behind enlargement 32 is slightly smaller than the external diameter of the tube and considerable pressure must be applied to the cap to push it farther onto the tube to the position shown in Figure 4. During the latter operation the length of tubing within the wall portion 38 is contracted slightly to provide a press fit therebetween.

When the end of tube 20 reaches the curved surface 40, it continues to follow the contour of the wall and, consequently, is contracted or curved inwardly, as shown in Figure 5. It will be readily appreciated that as the cap 22 is pro-

gressively forced onto the tube 20, the resistance offered by the latter becomes greater. When the resistance is sufficiently great, the tube 20 yields at the point 42 where it enters wall portion 38 and expands radially against the circumferentially enlarged wall portion 36. The expanded portion of the tube is designated by the numeral 44 and, as shown in Figure 6, it closely follows the outline of the enlargement and is pressed solidly against the wall of the latter.

As soon as the tube expands radially in the manner hereinabove described, resistance to further movement of the cap 22 becomes so great that the portion of the tube extending between the cap and the gripping jaws upsets, as at 46, against the inner end of the cap. This step is shown in Figure 7 and, as soon as it occurs, the capping operation is complete.

In practice, the entire operation can be performed rapidly and with very little danger of damage to the parts. The interlocking engagement between the cap and the rod holds the former solidly united with the tube.

If it is necessary or desirable to make the tube 20 stronger and relatively larger in diameter as shown in Figures 8 and 9, the end caps 22 and 24 are preferably maintained small in order to minimize the weight of the push rod. Therefore, the ends of the rod are spun down or otherwise reduced in diameter to provide terminals 48 of substantially the same diameter as the internal annular surfaces 38 of the caps. The terminals 48 are joined to the tube 20 by annular tapered shoulders 50 and the mouths 34 of the caps are made slightly larger in diameter than the external diameter of the tube. Thus, when the tube is held and the caps 22 and 24 applied thereto in the manner hereinabove described with reference to the first form of the invention, a snug or light press fit is provided between the terminals 48 and the cylindrical wall portions 38. When the annular shoulders 50 engage the inner tapered surfaces of the circumferential enlargements 36, they provide sufficient resistance so that the tube expands radially into the enlargements and upsets against the inner edges of the caps as best shown in Figure 9.

As suggested, the push rod construction shown in Figures 8 and 9 conveniently may be used whenever it is necessary or desirable to employ a relatively large rod 20 but undesirable correspondingly to increase the size and weight of end caps 22 and 24. By maintaining the end caps small, a substantial saving in weight results and this is an exceedingly important factor in a device of this character.

Reference is now had to Figure 10 which shows a modified type of end cap. In this form of the invention, the end cap is designated by the numeral 52 and is provided with a spherically curved, concave end wall 54 and an inwardly tapered cylindrical side wall 56. In the end wall 54 is an oil opening 58 which permits a lubricant to circulate through the push rod and to the bearings at each end thereof in the conventional manner.

The mouth 60 of cap 52 snugly receives the tube 20 and the cap can be easily pushed on the tube until the latter engages the end 54. Continued axial pressure against the cap 52, while maintaining the tube 20 stationary in the manner hereinabove described, causes the inner spherical surface of the end 54 to spread the tube solidly against the wall 56 and the portion of the tube extending between the cap and the clamping jaws to upset, as at 62, against the inner end of the

cap. It will be observed that the spread portion of the tube 20 which seats solidly against the inner surface of wall 56 cooperates with the upset portion 62 to hold the cap 52 firmly united with the tube.

It is to be understood that the form of the invention herewith shown and described is to be taken as a preferred example of the same and that various changes in the size, shape and arrangement of parts may be resorted to without departing from the spirit of the invention or the scope of the appended claims.

Having thus described the invention, I claim:

1. An engine push rod comprising an elongated rod, and a cap on at least one end of the rod, the side walls of said cap being circumferentially enlarged intermediate its ends, the portion of the rod in said cap entering said enlargement and the portion of the rod extending from and immediately adjacent to the cap being circumferentially enlarged and bearing against the end of the cap.

2. An engine push rod comprising an elongated rod, and caps on the ends of the rod, the side walls of each cap being circumferentially enlarged intermediate its ends, the portions of the rod in said caps entering said enlargements and the portions of the rod extending from and immediately adjacent to the caps being circumferentially enlarged and bearing against the ends of the caps.

3. An engine push rod comprising an elongated relatively thin-walled metal tube, and caps on the ends of the tube, the side walls of each cap being circumferentially enlarged intermediate its ends, the portions of the rod in said caps having radial extrusions which enter the enlargements of said caps, and the portions of the rod extending from but immediately adjacent to the caps having radial extrusions which bear against the ends of the caps, said extrusions within the caps and said extrusions outside the caps coacting to hold the caps securely on the terminal portions of the rod.

4. An engine push rod comprising an elongated relatively thin-walled metal tube, and caps on the ends of the tube, each of said caps having a spherically curved end portion and being circumferentially enlarged intermediate its ends, the ends of the rod seating solidly against the ends of the

caps, said rods also provided with radial extrusions which enter the circumferential enlargements and additional radial extrusions which bear against the inner ends of the caps.

5. An engine push rod comprising an elongated relatively thin-walled metal tube and a cap on the end of the tube, said cap having a convex outer end and being circumferentially enlarged intermediate its ends, the end of the rod within said cap being curved inwardly and seating solidly against the end of the cap, said rod also provided with a radial extrusion which fits snugly within the circumferential enlargement and a separate radial extrusion which bears against the inner end of the cap.
- 10 6. An engine push rod comprising an elongated relatively thin-walled metal tube, and a cap on the end of the tube, the outer end of said cap being concave and the side wall thereof being inwardly tapered, the end of the tube seating solidly against the end of the cap and the terminal portion of the tube being flared and seating solidly against the side wall of the cap, and a radial extrusion in said rod bearing against the inner end of the cap and coacting with the flared terminal portion thereof to hold the cap securely on the rod.
- 20 7. An engine push rod comprising an elongated rod, and a cap on at least one end of the rod, the side walls of said cap having a radially enlarged portion spaced axially from the inner end thereof, a portion of the rod in said cap entering said radially enlarged portion and a portion of the rod extending from and immediately adjacent to the cap being circumferentially enlarged and bearing against the end of the cap.
